UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, LONDON, ENGLAND, A BRITISH COMPANY.

PRACTICE-TUBE ADAPTER FOR QUICK-FIRING GUNS.

Application filed September 20, 1922. Serial No. 589,334.

To all whom it may concern:

Be it known that we, Sir ARTHUR TREVOR DAWSON, bart, and Sir GEORGE THOMAS BUCKHAM, knight, both subjects of the King 5 of Great Britain, residing at Vickers House, Broadway, Westminster, in the county of London, England, have invented certain new and useful Improvements in or Relating to Practice-Tube Adapters for Quick-Firing 10 Guns, of which the following is a specification.

This invention relates to ordnance having breech mechanism of the wedge or sliding block type and has for its object to provide 15 improved means for detachably holding a small-calibre practice tube within the bore of the gun, the said practice tube provided with its own breech or bolt mechanism and firing mechanism as is well understood.

According to the present invention the 20 practice tube is held in position longitudinally within the bore of the gun by means of catches adapted to engage with the rear walls of the grooves in the breech recess in 25 which the breech block slides. A device may be provided for forcing the practice tube and its associated parts rearwards so as to ensure proper contact between the catches and the rear walls of the grooves in which 30 the breech block slides and this device is so constructed and arranged that when it is in the operative condition it positively holds the said catches in their operative position.

In order that the said invention may be 35 clearly understood and readily carried into effect the same will now be described more fully with reference to the accompanying drawings, in which:—

Figures 1, 2 and 3 are respectively a rear 40 elevation, a vertical longitudinal section and a plan of the breech end of a gun provided with a practice tube constructed according to our invention.

Figures 4 and 5 are local sections taken 45 approximately on the lines 4, 4 and 5, 5 of Figures 3 and 1.

Figure 6 is a side elevation on a larger scale of a detail hereinafter referred to, and

Figure 7 is a section taken approximately 50 on the line 7, 7 of Figure 6.

A represents the breech end of the gun. B represents the breech recess in which the breech block slides, B', B' represent the aforesaid grooves in the breech recess, C rep-

resents the practice tube and D, D represent the aforesaid catches engaging with the rear walls of the grooves B', B' to hold the practice tube in position longitudinally within the bore of the gun.

In the construction shown the practice tube is constituted by the barrel of a service rifle which barrel is used complete with the bolt action of the rifle. The sear E of the trigger mechanism of this bolt action is shown as being arranged to be actuated at 60 will either by an electro-magnet E' or by a lanyard attached to a lever E² suitably connected to the sear in the manner described in the specification of our prior Patent No. 241 of 1906. The rifle is carried by a sleeve or 70 adapter F which is made so that it fits in the gap formed in the rear wall of the breech recess B for the passage of cartridges when loading the gun and has a foot piece F' resting upon the lower wall of this gap as 75 shown in Figure 2. The said adapter also has a forwardly extending cup-shaped member F² which fits in the cartridge chamber of the gun and serves, in conjunction with the aforesaid foot piece, to centre the practice tube with respect to the bore of the gun. The adapter F is attached to the rifle by means of a clip made in two parts G, G', the lower part G' of which engages with the existing lug C' on the rifle. The said clip 80 encircles part of the rifle barrel and is screwed into the rear part of the adapter so that the shock of firing is transmitted through the rifle lug C' to the clip G, G' and from the latter through the screw 90 threads to the adapter F. The two parts of the said clip are held together by the engagement of the screw threads with the adapter and a box or casing E³ in which the electro-magnet E' is mounted is held in position by means of a screw E⁴.

The aforesaid catches D, D are, in the construction shown, in the form of spring controlled plungers mounted transversely in the adapter F and controlled by a compression spring D' which is common to both the plungers. The front surfaces of these plungers are preferably curved or bevelled as shown so that the plungers will be forced inwards against the resistance of their spring by the engagement of the said surfaces with the rear walls of the breech recess during the insertion of the practice tube

into the gun. The said plungers D, D have upwardly extending finger pieces d, d by which the plungers can be moved to their disengaging position for the withdrawal of 5 the practice tube complete with its associated parts. H is the aforesaid device for pressing the practice tube and its parts rearwards so as to ensure proper contact between the spring plungers D, D and the 0 rear walls of the grooves B', B'. This device in the example shown is in the form of a spindle having a screw-threaded portion which engages with a nut F^x on the aforesaid adapter F, this spindle having at 5 its forward end a revolvable shoe H' adapted to press against the breech face of the gun; thus when the said spindle is revolved by means of a handle H² provided at its rear end, the practice tube and its parts can 0 be forced rearwards as stated above. The said nut F^x is trunnioned at f^x, f^x to enable the spindle H to be turned from the operative position in which part of it lies between the aforesaid finger pieces d, d of the 5 spring controlled plungers D, D to positively hold the latter in their engaging position, into an inoperative position in which the spindle is clear of the said finger pieces so as to enable the said plungers to be 0 moved out of engagement with the aforesaid grooves B', B' for the removal of the practice tube and its parts.

The above described practice tube is used in the gun without the gun breech mechanism having to be dismantled or modified in any way, the breech actuating mechanism being merely operated to shift the breech block into a partly open position clear of the adapter F so as to enable the latter to 0 be placed in position.

What we claim and desire to secure by Letters Patent of the United States is:—

1. The combination with a small-calibre practice tube for use in a gun having breech mechanism of the sliding block type, of locking means for engaging with the rear walls of the grooves in the breech recess in which the breech block slides.

2. The combination with a small-calibre practice tube for use in a gun having breech mechanism of the sliding block type, of locking catches for engaging with the rear walls of the grooves in the breech recess in which the breech block slides.

3. The combination with a small-calibre practice tube for use in a gun having breech mechanism of the sliding block type, of spring controlled locking catches for engaging with the rear walls of the grooves 0 in the breech recess in which the breech block slides.

4. The combination with a small-calibre practice tube for use in a gun having breech mechanism of the sliding block type, of locking catches for engaging with the rear walls

of the grooves in the breech recess in which the breech block slides and a device for forcing said practice tube rearwards so as to ensure proper contact between said catches and said rear walls.

5. The combination with a small-calibre practice tube for use in a gun having breech mechanism of the sliding block type, of locking catches for engaging with the rear walls of the grooves in the breech recess in 70 which the breech block slides, a device for forcing said practice tube rearwards so as to ensure proper contact between said catches and said rear walls, and means whereby said device, when in its operative position, positively holds said catches in their engaging position.

6. The combination with a small-calibre practice tube for use in a gun having breech mechanism of the sliding block type, of 85 spring-controlled locking catches for engaging with the rear walls of the grooves in the breech recess in which the breech block slides and a device for forcing said practice tube rearwards so as to ensure proper contact between said catches and said rear walls. 90

7. The combination with a small-calibre practice tube for use in a gun having breech mechanism of the sliding block type, of 95 spring-controlled locking catches for engaging with the rear walls of the grooves in the breech recess in which the breech block slides, a device for forcing said practice tube rearwards so as to ensure proper contact between said catches and said rear walls, and means whereby said device, when in its operative position, positively holds said catches in their engaging position.

8. The combination with a small-calibre practice tube for use in a gun having breech mechanism of the sliding block type, of locking catches for engaging with the rear walls of the grooves in the breech recess in which the breech block slides, a screw-threaded spindle for bearing at its forward end against part of the gun and a trunnioned nut in which said spindle engages, the rear part of said spindle being so formed that it will positively hold said catches in the engaging position when said spindle is moved to the operative position.

9. The combination with a small-calibre practice tube for use in a gun having breech mechanism of the sliding block type, of 110 spring-controlled locking catches for engaging with the rear walls of the grooves in the breech recess in which the breech block slides, a screw-threaded spindle for bearing at its forward end against part of the gun and a trunnioned nut in which said spindle engages, the rear part of said spindle being so formed that it will positively hold said catches in the engaging position when said spindle is moved to the operative position.

10. A practice tube adapted for use in a 120

gun having breech mechanism of the sliding block type, said adapter being intended to receive a practice tube constituted by the barrel of a service rifle, in combination with locking means carried by said adapter for engaging with the rear walls of the grooves in the breech recess in which the breech block slides.

11. A practice tube adapter for use in a gun having breech mechanism of the slid-

ing block type, said adapter being intended to receive a practice tube constituted by the barrel of a service rifle, in combination with spring-controlled locking catches carried by said adapter for engaging with the rear ¹⁵ walls of the grooves in the breech recess in which the breech block slides.

ARTHUR TREVOR DAWSON.
GEORGE THOMAS BUCKHAM.
